[57] **CLAIM**

The ornamental design for combined emergency warning light and control unit therefor for a vehicle or the like, as shown and described.

DESCRIPTION

FIG. 1 is a top, front perspective view of a combined emergency warning light and control unit therefor for a vehicle or the like showing my design;

FIG. 2 is a front elevational view of the emergency warning light, the control unit being omitted for convenience of illustration;

FIG. 3 is a rear elevational view thereof;

FIG. 4 is an end elevational view thereof;

FIG. 5 is an opposite end elevational view thereof;

FIG. 6 is a top plan view thereof;

FIG. 7 is a bottom view thereof;

FIG. 8 is a front elevational view of the control unit, the warning light being omitted for convenience of illustration;

FIG. 9 is a rear elevational view thereof;

FIG. 10 is a side elevational view thereof;

FIG. 11 is an opposite side elevational view thereof;

FIG. 12 is a top plan view thereof; and,

FIG. 13 is a bottom plan thereof.
